H. CARSE,
Filling Bottles.

N° 42,559.

Henry Carse

UNITED STATES PATENT OFFICE.

HENRY CARSE, OF PITTSBURG, PENNSYLVANIA.

IMPROVEMENT IN BOTTLING SODA-WATER UNDER PRESSURE.

Specification forming part of Letters Patent No. 42,559, dated May 3, 1864.

To all whom it may concern:

Be it known that I, HENRY CARSE, of Pittsburgh, in the county of Allegheny and State of Pennsylvania, have invented a new and useful Improvement in Machines used for Bottling Soda-Waters or Liquids Under Pressure; and I hereby declare that the following is a full, clear, and exact description thereof, reference being had to the accompanying drawings, forming part of this specification, and to the letters of reference marked thereon.

In all machines heretofore in use for this purpose the charging-cylinder is provided with an escape-valve so regulated as to allow the surplus gas to escape to prevent the strong outward pressure from bursting the bottle undergoing the operation of filling. As the gas escapes it carries over with it a small portion of the acidulated water, and also the sirup used in flavoring, at each stroke of the machine, this gas and water, as well as the sirup, being actually wasted, for previous to my invention no means had been devised for preventing this loss.

The object of my invention is to save this sirup and water that was allowed to pass off, and for this purpose I attach to the charging-cylinder (in place of the old escape-valve) a small fluid-chamber, communicating with the interior of the charging-cylinder by means of a short pipe and faucet, the lever of this faucet being attached or connected to the cross-bar carrying the cork-driver, and operating in such a manner as that when the cork is placed in the mouth of the charging-cylinder, and is partly driven down, the faucet will open to allow the surplus gas and water, as well as the sirup, to enter the chamber. As soon as the cork is driven into the bottle the faucet closes, and remains closed until the next or succeeding bottle is placed in position to be filled and the cork inserted in the mouth of the charging-cylinder, when, as the cork is being driven down, the faucet opens, the pressure of the gas in the chamber forcing the fluid into the bottle in advance of the cork, thus saving that which previous to my invention was allowed to pass off and go to waste.

To enable others skilled in the art to understand and make my improvement, I will pro-

ceed to describe its construction and operation by reference to the accompanying drawings, in which—

Figure 1 represents a perspective view of my invention ready to be attached to a bottling-machine. Fig. 2 represents a vertical section of the same. Fig. 3 represents a longitudinal transverse section of the faucet and part of the pipe.

All the parts are lettered, and similar letters denote corresponding pieces in the several views.

I construct my invention by forming a small metal fluid-chamber, A, of any desirable shape, having an opening, N, Fig. 2, at the top, and a corresponding opening, G, Fig. 2, at the bottom, the opening at the top being closed by a valve, t, held down by a strong spiral spring, s, Fig. 2, kept in place by a tube, R, covered by a screw-cap, B, having a hole through it for the guidance of the valve-stem T, around which the spiral spring passes. The bottom of this chamber is attached to a short curved pipe, L, one end of which is screwed into the charging-cylinder directly opposite the supply-pipe. Between the chamber A and the charging-cylinder of the machine is a faucet, C, operated by a long lever, D, and secured in place by a bolt, P, and screw-nut y, having a leather washer, x, placed between the working parts to prevent cutting and subsequent disarrangement.

The operation of my invention is as follows: The screw y being inserted in an opening for that purpose made in the charging-cylinder opposite the supply-pipe, as hereinbefore stated, the end of the faucet-lever D is connected by link or otherwise to the cross-bar of the cork-driver, which, as it approaches the completion of its upward motion, raises the faucet-lever D to the position shown by the dotted lines in Fig. 1. This closes the faucet until the cork is forced partially down by the driver, when the faucet is opened and the surplus water and sirup allowed to enter the chamber A through the openings m and F in the pipe L, where it is retained until the next or succeeding bottle is placed in position to be filled. By this time another cork is inserted in the upper end of the charging-cylinder and

partially forced down toward the mouth of the bottle, when the faucet C is turned and the contents of the chamber A is forced by the expansion of the gas into the bottle placed to receive it.

The valve *t*, at the top of the chamber A, is intended to regulate the pressure of the gas as it enters therein to suit the pressure in the fountain; so that when the faucet C is opened the contents of the chamber will be forced by the expansiveness of the gas into the bottle in advance of that fluid that comes from the reservoir. The proper degree of pressure necessary to accomplish this result is brought about by the operator turning the screw-cap B, which releases or presses down the spiral spring *s* on the valve *t*. As this invention is intended to be applied to the ordinary bottling-machines in use, a description of them is herein deemed unnecessary, as the

principles of their construction and operation are well known.

Having thus described by invention, what I claim is—

1. The application and use of a fluid-chamber attached to the charging-cylinder of a bottling-machine for the purpose of saving the surplus sirup and water passing off while filling one bottle, and forcing it into the succeeding bottle in advance of the fluid that comes from the reservoir, substantially in the manner and for the purposes herein set forth.

2. The combination of the faucet C and escape valve *t* with the fluid-chamber A and pipe L, when arranged and operating as hereinbefore stated, for the purposes set forth.

HENRY CARSE.
